UNITED STATES PATENT OFFICE

ROY M. HALL, OF VALPARAISO, INDIANA

MONTHLY-YEARLY CALENDAR PAD

Application filed October 25, 1930. Serial No. 481,293.

My invention relates to improvements in monthly-yearly calendar pads, and it more especially relates to the features pointed out in the annexed claims.

5 The purpose of my invention is to provide a composite calendar pad which comprises a group of twelve monthly sections; that makes each group a complete calendar for a given month; that provides a suitable stiff backing 10 to which the entire pad is fastened by any suitable means; that has imprinted on all of the sheets of a given month the twelve months of a year in duplicate; in which on each succeeding monthly group the first listed month 15 is advanced one month over the first month of the previous group, etc., throughout the entire year; in which each monthly group on each sheet has printed the seven days of the week advancing day by day from sheet to sheet; that provides a pair of slidable indicators, one 20 to be used on the backing adjacent the different months of the year, and the other to be used on the backing adjacent the days of the week; that utilizes an indicating guide which 25 can be slid along on the backing and at the same time raised and lowered to accommodate the different thicknesses of the groups remaining after a selected period; and that also 30 provides a memorandum space on each pad sheet.

With these and other ends in view, I illustrate in the accompanying drawing such instances of adaptation as will disclose the broad underlying features of my invention, 35 without limiting myself to the specific details shown thereon and described herein.

Figure 1 is a front elevation of a group of calendar sheets assembled on a portion of a backing and associated with the monthly and weekly indicators.

Fig. 2 shows only a fragment of the first sheet of each of the second, third and fourth month groups.

Fig. 3 is a transverse cross section of a portion of the pad showing the relation of an indicator to the thickness of the pad.

Fig. 4 shows three successive portions of the first, second, and third sheets of each month, designating the successive progress of the days of the week from sheet to sheet.

Fig. 5 is an enlarged isometric view of one of the indicators.

Fig. 6 is a reduced size front elevation of a pad attached to a complete backing.

In using my invention I may adapt and 55 adopt whatever alternatives or equivalents the exigencies of varying conditions may demand without departing from the broad spirit of the invention.

My pads 7 are mounted on a backing 6 by 60 means of any desired fastenings 5. Along the left hand edge of the backing 6 an indicator 12 may be slid so that its pointer 13 will stand opposite the corresponding month of the monthly portion of the pad that is 65 being used. The indicator 12 has a clamping portion 14. This part will be more or less springy so as to hold the indicator in place while the portion 12 is more or less flexible, as shown in dotted lines in Fig. 3, to adapt 70 itself to the thickness of the pad, which at the beginning of a year will in height be the aggregate of twelve monthly groups of 31 sheets each.

The months are printed along the left of 75 each sheet at 11. For a given month the indications 11 are in duplicate, for the next monthly group the name of the first month on each sheet is advanced one month over that on each sheet of the preceding month. For instance in Fig. 1 the pointer 13 is opposite January. As soon as all of the January sheets have been used and detached the pointer 13 can remain at the same point, but for 80 the second group it will indicate February. When all the sheets of this month are detached the pointer will then indicate March, 85 and so on throughout the entire year.

By reason of not having the year printed 90 on the pad it is available for immediate use commencing at any time of the year; for instance, supposing instead of January being the first selected month, as indicated on Fig. 1, June, August, October, or any other month, happen to be the first month in which the pad is put into use. The indicator 12 with 95 its pointer 13 is placed opposite the name of the starting or selected month when it will be found in proper position for all the following months grouped on the backing. 100

By reason of this unique provision my pads are available at any time and the large losses incurred through printing pads for the fixed months and days of each month of a fixed year is entirely avoided. If the user cares to mark the year of adoption in pencil, or otherwise, on each sheet, and should he care to file the detached sheets because of any memorandum data noted in the space he may do so, but his voluntary procedure does not limit the relation of all the succeeding sheets of the pad.

In Fig. 2 is shown fragments of a completed pad comprising at 8 the first sheet of the second month, at 9 the first sheet of the third month and at 10 the first sheet of the fourth month. Supposing the pointer is arbitrarily set at September instead of January as shown, a dotted line to the left will show that it will be in position for the October group, and also for the following month of November, the succeeding month of December, the next month January, etc., etc.

In order that the corresponding days of the week of a given month may be indicated, a pointer 13 positioned along the bottom edge of the backing 6 is placed opposite the name of the first day of the week corresponding to the first day of the selected month indicated by the pointer on the left hand edge of the backing 6.

When all the sheets 1, 2, 3, etc. of a given month have been detached, the pointer opposite the days of the week 4 will be shifted to the day of the week corresponding to the first week day of the first numbered day of the next month, where it will remain until all the sheets of that month have been detached when it will be again shifted to correspond to the first day of the week on which the first of the next month occurs.

If all of the months of a year had exactly the same number of days then the week day pointer, after having been positioned to the day of the week corresponding to the first day of a starting month, would not need to be changed over the entire year.

The separate sheets of each monthly group bear the numerals from 1 to 31 inclusive and are of course repeated from month to month. I do not limit myself to the use of twelve monthly groups secured to a backing as it is obvious that a single month can be used on the backing or the monthly groups covering three months, six months or any other combination. However, it is apparent that the greatest benefit will accrue to the producer and user if more monthly groups than a single month are assembled on a single support. An opening 16 at the top of the support serves to suspend the calendar on a wall.

It is obvious that my calendar will effect large economies in production and entirely eliminate the waste now incurred by the producer and the user, thus attaining a result

that has hitherto been impossible, on account of which this invention is claimed in its broadest aspects.

What I claim is:

1. In calendar pads, a plurality of separate groups of sheets the sheets of each group numbered consecutively from 1 to 31, monthly indicia imprinted near one edge of each sheet comprising all the months of a year such indicia being in duplicate for a single monthly group, the monthly indicia of succeeding monthly groups advancing month by month all the indicia of all the groups bearing the same spaced apart relation to each other, a suitable support, means for holding the sheets assembled on the support, an adjustable indicator slidable on the support adjacent the monthly indicia, an imprint of the seven days of a week adjacent the edge of each sheet of a given month imprinted opposite each other and advancing day by day from sheet to sheet, and an indicator movable on the support adjacent the imprinted days of the week.

2. In calendar pads, a plurality of separate groups of sheets the sheets of each group having printed thereon numbers running consecutively from 1 to 31 from sheet to sheet, monthly indicia imprinted near one edge of each sheet including all the months of a year, an imprint of seven days of a week adjacent the edge of each one of the 31 sheets positioned opposite each other and advancing day by day from sheet to sheet, a suitable support to which the sheets are attached, a separate indicator slidable on the support adjacent the imprinted months and adjacent the imprinted days of the week.

In testimony whereof I affix my signature.

ROY M. HALL.
